UNITED STATES PATENT OFFICE.

PETER S. STEPHENS, OF WASHBURN, ILLINOIS.

WHEEL-HOLDER.

SPECIFICATION forming part of Letters Patent No. 656,057, dated August 14, 1900.

Application filed November 7, 1898. Serial No. 695,716. (No model.)

To all whom it may concern:

Be it known that I, PETER S. STEPHENS, a citizen of the United States, residing at Washburn, in the county of Woodford and State 5 of Illinois, have invented a new and useful Wheel-Holder Machine, of which the following is a specification.

My invention relates to certain new and useful improvements in wheel-holders, by means 10 of which a supporting and retaining device is provided for vehicle-wheels, being simple in construction, durable, and cheap at first cost.

My invention has for its object the provision of a suitable frame-support, upon which 15 it is purposed to place and hold a vehicle-wheel of a vertically-carried rod fastened to the base of said support, a lever pivoted upon said frame through which suitable mechanism is actuated, which is engaged by said vertical rod purposed to automatically engage 20 the hub of a vehicle-wheel and hold the same firmly upon said frame-support, of the means for releasing said mechanism, and of certain other details hereinafter more fully described, 25 and pointed out in the appended claims.

That my invention may be more fully understood, reference is had to the accompanying drawings, in which—

Figure 1 is an elevation of my wheel-support, the same shown in its normal position, and of a vehicle-wheel shown thereon in dotted lines. Fig. 2 is an enlarged sectional elevation of the main working parts, a portion of the figure shown broken away. Fig. 3 is 35 a cross-section showing the means of fastening the lever.

In the drawings, A is a circular bearing-plate supported on a suitable base A' by means of the braces a, extending up therefrom, the 40 forward braces being omitted. The base A' is provided with suitable means whereby it may be bolted to the floor, as shown at a' in the drawings.

B is a vertically-carried bar or rod, the lower 45 end of which is suitably fastened in the base A'. The upper end of the bar or rod B enters a hollow cylinder B' of suitable length, which is preferably of gas-pipe. C is a similar hollow cylinder or gas-pipe of smaller diameter 50 than the cylinder B', which forms an elonga-

tion thereof to which it is connected by the reducer C'.

D is a plunger carried in the hollow cylinder C, provided with a head d on its lower end, and d' is a coil-spring interposed between the upper end of the bar or rod B and the head d and loosely carried in the cylinder B'. 55

E is a suitable locking mechanism carried within the cylinder C and at a point near its upper end, consisting of a pivotally-carried 60 lug e, the same being pivoted at e' in the cylinder and in such a manner that the normal position of the locking device will be in a vertical position. e² shows slots in the cylinder, the function of which will be hereinafter described. 65

F is a lever suitably pivoted at f to one of the braces a and has a pivotal connection with a cleat f', which is loosely carried on the ring or loop f², bolted or otherwise securely fastened to the hollow cylinder B'. The forward end of the lever is carried between two braces a, one of which is provided with a number of ratchet or cog teeth a², purposed to be engaged by a plate extension f³, fastened to 70 the lever, or may be a part of the same if it is so desired. 75

G is a coil-spring carried around the cylinder B' and the rod B between the ring f³ and the base-plate A', purposed to hold the cylinder B' under compression. 80

When it is purposed to hold a vehicle-wheel on the frame-support, the same is laid upon the bearing-plate A, as shown in Fig. 1, and in such a manner as to have the cylinder C 85 protruding through the center of the hub of said wheel. The lever F is caused to be lowered by pressure thereupon, which will by its downward pressure cause the cylinder B' to descend and through the spring d', carried 90 therein, which has a bearing relation with the bottom of the plunger, raise the same, the upper end engaging with the lower end of the lug e, and the same presenting a cam-face will be raised in a horizontal position and by 95 the downward movement of the cylinder C, which is simultaneous with the upward movement of the plunger, the lug e will be caused to engage the hub of the wheel. The more pressure applied to the lever the firmer the 100

lug will engage the hub, the same being retained in position by engagement of the plate extension f^2 on the lever with the cogs in the brace a . By releasing the lever F the parts hereinbefore described as actuating the locking mechanism will be released and the same forced back into their normal positions by the coil-spring G .

Having thus fully described my invention, what I claim, and desire to secure by Letters Patent, is—

1. In a wheel-support, the combination of a main frame, of a locking-lever pivoted to said frame and having a pivotal connection with a vertically-movable cylinder, a locking mechanism pivoted in said cylinder, and of the mechanism adapted to automatically engage said locking device when the cylinder is lowered, all substantially as described and shown.
2. In a wheel-support the combination with a stationary bar or rod B , a telescoping cylinder carried above said rod, of a locking device pivotally carried in said cylinder at or near its outer end, a plunger loosely carried in said cylinder, of the mechanism for lowering said cylinder causing the upper end of said bar or rod to engage with said plunger

for actuating the locking device carried in the cylinder, substantially in the manner 30 herein shown.

3. In a wheel-support, a base-plate and a vertically-carried rod therefrom, of a cylinder telescoping on said rod and a lever pivotally secured thereto, of a locking device 35 consisting of a lug pivotally carried in the upper end of said cylinder and purposed to be engaged by a plunger carried therein when the cylinder is lowered by means of said lever, causing a contact of said plunger with the 40 locking device by the rod on the base-plate, in the manner described.

4. In a wheel-support, the combination with a main frame, of the bar or rod B , the telescoping cylinder B' , having the elongated reduced 45 portion C , of the locking device consisting of the lug e , arranged to be actuated by a plunger carried within said cylinder, lever F , arranged to actuate the cylinder B' , which when lowered will cause the locking device to be 50 automatically set by the plunger engaging therewith, all substantially as set forth.

PETER S. STEPHENS.
